PORTABLE STEAM GENERATOR AND
STEAM IRONMarshall B. Young, New York, N. Y., assignor to
Floor-O-Matic, Inc., New York, N. Y., a corpora-
tion

Application January 28, 1948, Serial No. 4,741

1 Claim. (Cl. 38—77)

1 This invention relates to improvements in electric-steam pressing irons and more particularly has reference to a device of the character described wherein two units, suitably connected are provided. One unit comprising a stationary stand and electrically energized steam generator and the second unit comprising a hollow bodied pressing iron to which low pressure steam is fed, through a flexible tubular connection, from the said steam generator and in which an electrically energized heating element is contained within the said pressing iron to superheat the steam after same has entered a steam chamber in said pressing iron.

An object of this invention is to provide an electric-steam pressing device of the character described wherein the steam is generated in a separate unit and is fed to the pressing iron through a flexible tube which connects the said iron with the said steam generator.

Another object of this invention is to provide an electric-steam pressing device of the character described wherein the said generator and the said pressing iron are separately electrically energized—the first mentioned unit acting as a steam generator and the second unit or said pressing iron being adapted to superheat the steam it receives from the said steam generator.

A further object of this invention is to provide an electric-steam pressing device of the character described wherein means are employed for electrically heating the said pressing iron independently of the steam fed to same by the said steam generator.

A further object of this invention is the provision in an electric-steam pressing device of the character described wherein the steam generator may be employed as a stand for holding the said pressing iron when same is not in use.

Another object of this invention is the provision in an electric-steam pressing device of means upon the said pressing iron for directing steam through suitable orifices in the sole or bottom plate of the said pressing iron.

A further object of this invention is the inclusion in an electric-steam pressing device of the character described of means attachable to the said pressing iron to render the same adaptable for use by an ambidextrous or left handed operator.

A further object of this invention is the provision in an electric-steam pressing device of means upon the said generator for controlling the steam pressure therein and means upon the said pressing unit for controlling the superheating

member thereon and a manually actuated valve means also upon the said pressing unit for controlling the steam flow through the orifices in the said sole or bottom plate of said pressing iron.

2 A still further object of this invention is the provision of an organization in which the constituent elements are so arranged structurally and functionally as to assure improved results with materials and members which may be manufactured at reasonable cost, may be easily assembled and which will be efficient in operation with minimum wear to the parts.

The invention possesses other objects and features of advantage some of which, with the foregoing, will be set forth in the following description and in the claim wherein parts will be identified by specific names for convenience, but they are intended to be as generic in their application to similar parts as the art will permit.

20 In the accompanying drawings there has been illustrated the best embodiment of the invention known to me, but such embodiment is to be regarded as typical only of many possible embodiments, and the invention is not to be limited thereto.

The novel features considered characteristic of my invention are set forth with particularity in the appended claim. The invention itself, however, both as to its organization and its method of operation, together with additional objects and advantages thereof, will best be understood from the following description of a specific embodiment when read in connection with the accompanying drawings, in which:

35 **30** Figure 1 is a front elevational view of the device showing the pressing iron resting upon the steam generating unit.

Figure 2 is an end view of same and shows the pressing iron removed from the steam generator.

Figure 3 is a top or plan view of the steam generator.

Figure 4 is a top or plan view of the pressing iron.

Figure 5 is an end elevational view of a part of the steam generator.

Figure 6 is a detail of an attachment to be applied to the valve operating handle upon the pressing iron and will be hereinafter described.

Figure 7 is a detail showing the means employed for suspending the flexible tube connection of the device.

Figure 8 is a plan view of the steam generator with part of the top broken away and having various parts disconnected therefrom.

Figure 9 is a transverse section of the steam generator taken along the line 9—9 of Figure 8.

Figure 10 is a plan view of the pressing iron with a portion of the top broken away and with parts removed therefrom.

Figure 11 is a longitudinal section, in elevation, taken along the line 11—11 of Figure 10.

Figure 12 is a transverse section taken along the line 12—12 of Figure 10.

Figure 13 is an enlarged detail elevational view of the steam controlling valve upon the pressing iron.

Figure 14 is a sectional elevational view of same along line 14—14 of Figure 13.

Figure 15 is a sectional elevational view of a relief or safety valve upon the steam generator.

Figure 16 is a sectional view taken along line 16—16 of Figure 15.

Figure 17 is a plan view, partly broken away of a heating unit in the pressing iron.

Figure 18 is a side elevational view of same.

Figure 19 is a bottom view of the sole or bottom plate of the pressing iron and shows steam orifices therein.

Figure 20 is a sectional elevational view of same and is taken along line 20—20 of Figure 19.

Referring in detail to the parts 11 designates the housing of a steam generator having an up-standing rear portion 12 and a higher raised portion 13. The said generator housing 11 is formed with a stand or platform 14 upon which there is adapted to rest a pressing iron 15 connected to the said generator housing by means of a flexible tube or hose 16 attached thereto at 17 and at 18 to a steam chamber 19 formed in the said pressing iron 15.

The said generator housing 11 is formed with a water containing and steam generating chamber 20. A filler opening is provided in said housing and closed by means of a plug 21 and sealed by a washer 22. A drain off cock 23 may be provided to drain the generator housing when necessary. A pressure indicator 24 is attached to the generator housing at 25 and at 26 a relief valve 27 may be attached. An immersion heater unit 28 (Figures 8 and 9) extends through the side of the said housing 11 into the steam generating chamber 20 and is electrically connected with a thermostat in a housing 29 attached to the outside of the said generator housing. An electric current conductor 30 having a connection plug 31 upon its outer end furnishes a means for picking up current from a source of supply. A pointer knob 32 having a shaft extending into the housing 29 affords a means for controlling the heat generated by the said immersion heater unit 28.

As hereinbefore stated the hose 16 leads from the steam generating chamber 20 in the generator 11 to the steam receiving chamber 19 in the pressing iron 15 and is best illustrated in Figures 10, 11 and 12. The said pressing iron is made up of two principal parts. An upper body section 33 within which the said steam chamber 19 is formed and a lower section 34 known as the sole or bottom plate, the two sections being securely held together by means of screws 35. The sole plate 34 has bores or channels 36 and 37 extending in V formation as shown in Figure 19. From these channels, extending through the bottom wall thereof, are orifices 38 which provide steam outlets. The openings 39 and 40 of the bores 36 and 37 respectively are threaded to receive plugs, (not shown) to permanently close same after the channels having been bored. Tubular connection is made between the said

channels 36 and 37 with the said steam chamber 19 in the pressing iron and will be herein-after described.

Disposed and held securely in place between the said upper body section 33, in a recess 33' formed in the bottom of the said upper section 33, and the said lower section 34 is an electrical resistance unit 41 (Figures 11 and 12) which is electrically connected to a control unit 42 secured within a compartment 43 formed in approximately the central portion of the said upper section 33. A pointer knob 44 connected with the said control unit 42 provides a means for regulating the electric current flow to the unit 41. The construction of the said unit 41 is clearly shown in Figures 17 and 18. An upper and lower sheet of mica or other suitable insulating material, 45 and 46 respectively, both of which have a central opening 47, carry between them winder strips 48 and 49 also of mica and around which there is wound a continuous flat wire 50 of high electrical resistance. The ends 51 of the said resistance wire pass through perforations 52 and 53 in the said winder strips and out through perforations 54 in the upper sheet of mica, to the control unit and to an electrical conductor 55. The two said sheets of mica and the interposed mica winding strips are securely held together by rivets or eyelets 56. The said heating unit 41 is electrically energized by means of the said conductor 55 which leads into said compartment 43 and connects with the said control unit 42 and heating unit 41. The conductor 55 follows the line of the aforesaid hose 16, and connects with the thermostatic control in the housing 29. The free end of the said conductor being provided with a connector plug 57 which affords a means of attachment to the thermostat in the housing 29.

To one of the said pressing iron 15 there is attached, by screws 58, an upright valve member. (Figures 1, 2, 4, 13 and 14.) This valve member consists of an upright body 58' having a cut out portion 59 and an extending bracket 60 upon which there is pivotally mounted, at 61, a lever 62 (Figures 1 and 4). The said lever 62 has, upon its extended arm, a push button member 63 adapted to be depressed by the user's thumb.

The opposite or inner end 64 of the said lever 62 freely engages the lower side of a collar 65 securely attached, by means of a set screw 66, to a needle 67 slidable in said valve body 58'. A spring 68 engages around the upper portion of the said needle 67 and is disposed between the said collar 65 and an adjustable threaded nut 69 which engages through the top portion 70 of the said valve body 58'. The lower end of the said needle 67 is slightly contracted to form a needle point 71 which engages upon a seat 72 normally closing a channel 72'. The said channel 72' leads into a chamber 73 which connects, through a coupling member 74, to a tubular connecting member 75 in turn making a connection at 76 with the steam chamber 19 in the upper section 33 of the said pressing iron 15. A channel 77, in line with the said lower contracted portion of the said needle 67 leads through a coupling 78 to a tubular connecting member 79 which in turn is connected, at 80, through a coupling 81 with the channel 37 in the aforesaid sole plate 34.

The relief valve 27 consists of a tubular member (Figures 15 and 16), having a central upper bore 82 and a narrower concentric lower bore 83.

The upper end of the bore 82 is partially threaded to receive a cap member 84 having a recessed portion 85 adapted to seat the end of a spring 86. A pin 87 engages through the cap 84 and has a broadened end portion 88 to form a shoulder 89 and a concave seat 90 for a ball valve 91 which seats upon the upper end of the said bore 83. The said spring 86 engages around the pin 87 and is disposed between the said recess 85 in the cap 84 and the shoulder 89 upon the broadened portion 88 to normally keep the ball valve 91 upon its seat. Radially arranged channels 92 are formed at approximately the center of the valve member and provide a passage for escaping steam to the channels 92 and outer air when excessive pressure raises the ball valve against a fixed pressure of the spring 86.

The pressing iron 15 so far described is intended for use by an operator who uses the thumb of the right hand to depress the push button 63. However, to make the device readily usable by an ambidextrous or left handed operator a bracket 93 (see Figure 6) having a push button 94 is attached to the lever to bring the said push button 94 to the opposite side of a handle 95 which is attached to the pressing iron 15 by means of the uprights or brackets 96 and 97. An adjustable set screw 98 (Figures 1 and 4) may be provided upon the lever 62 to limit the downward movement of same.

A light tension spring 99 (Figure 7) which is attached to the tied together hose 16 and conductor 55, approximately in the central point of its length, may be provided to conveniently suspend the hose and conductor out of the operator's way.

To operate the device, the chamber 20 in the generator housing 11 is partially filled with water, the pressing iron 15 is placed upon the platform 14 of the generator, the plug 57 is connected in the receptacle 100 upon the thermostat housing 29 (Figure 8), the plug 31 of the conductor 30 connected to current supply receptacle, and the pointer knobs 32 and 44 adjusted to the desired point. The immersion heater unit 28 begins to warm up and current passing along conductor 55 begins to energize the heating unit 41 in the pressing iron 15. When sufficiently heated, the unit 28 will generate steam which will pass through the hose 16 to the steam receiving compartment 19 in the pressing iron 15 while at the same time the heating unit 41, being now sufficiently heated will superheat the steam in the chamber or compartment 19 thus drying out the moisture in the steam. The iron may now be sufficiently hot for use and during its use, when it is desired to direct steam out through the orifices 38 in the sole plate

34, the operator depresses the lever 62 thereby raising the needle 67 and opening the valve 71 to allow the dry steam to pass from the chamber 19 through the tube 75, coupling 74, chamber 73, valve 72, channel 77, coupling 78, tube 79 and coupling 81 into channels 37 and 38 from whence the dry steam passes out through the orifices 38.

The separation of the steam generator and the pressing iron into single units provides an advantage over devices of the said type which combine the steam generator and the pressing iron in a single unit. By separating the said units as hereinbefore set forth it is possible to provide a pressing iron having a minimum number of parts thereby decreasing its size and weight without impairing its efficiency in use.

I claim:

A portable steam generator and pressing iron connected therewith, the said steam generator comprising a water containing hollow body, an electrically energized immersion heater unit secured to the wall of the hollow body and extending into the water compartment of same to generate steam, a conductor supplying electrical energy to the immersion heater unit, a platform forming a part of the wall of said hollow body of the steam generator, a pressing iron adapted to rest upon said platform to receive preliminary heating from the generator, the said pressing iron having a steam channel therein and comprising a sole plate and a casing secured upon said sole plate, a flexible tube connecting the pressing iron to the steam generator adapted to supply steam to the steam channel in the pressing iron, an auxiliary electrically energized heating unit upon the pressing iron to superheat and dry the steam supplied thereto by the steam generator, and a conductor having connection with the electrical source to the steam generator to supply electrical current to the said auxiliary heating unit.

MARSHALL B. YOUNG.
